UNITED STATES PATENT OFFICE.

MILES JOSEPH BUCKLEY, OF WATERBURY, CONNECTICUT.

COUCH.

No. 821,333.

Specification of Letters Patent.

Patented May 22, 1906.

Application filed February 27, 1906. Serial No. 303,240.

To all whom it may concern:

Be it known that I, MILES JOSEPH BUCKLEY, a citizen of the United States, residing at Waterbury, in the county of New Haven and State of Connecticut, have invented a new and useful Couch, of which the following is a specification.

This invention relates to couches.

The object of the invention is in a novel and practical manner to obviate any tendency on the part of the side edges and foot of the upholstered portion of a couch to mash down, whereby the wearing qualities of the article will be measurably increased and its appearance materially enhanced.

A further object is to facilitate the attaching of the outer covering to the couch and also the formation of the tufting, quilting, or the like.

20 A still further object is to reinforce the bottom of the couch by the employment of spaced connecting-strips, which also serve to retain the marginal cushion when in position.

With these and other objects in view, as 25 will appear as the nature of the invention is better understood, the same consists in the novel construction of a couch, as will be hereinafter fully described and claimed.

In the accompanying drawings, forming a 30 part of this specification, and in which like characters of reference indicate corresponding parts, Figure 1 is a view in perspective of a couch constructed in accordance with the present invention, exhibiting a portion of the 35 covering torn away to display the springs and the marginal cushions employed for reinforcing the edges and foot portion of the couch. Fig. 2 is a view in vertical longitudinal section on an enlarged scale. Fig. 3 is a 40 view in vertical transverse section, showing certain parts that are concealed in Figs. 1 and 2.

The frame 1 of the couch may be of any preferred construction and is provided with the 45 usual legs 2 and head 3. Secured to the upper edges of the sides, footboard, and head is a woven-wire bottom 4, such as is generally employed in connection with bed-bottoms and which is stayed and prevented from sagging by coiled springs 5 of the usual construction, that bear at their upper ends against the under side of the bottom and are secured at their lower ends to transverse slats or strips 6.

In order to prevent the side edges and foot

of the couch-surface from mashing over and thus becoming distorted and unsightly, there is employed a marginal cushion 7, which surrounds the two edges and foot of the couch-surface and terminates at the head of the couch-frame. This cushion is composed of a strip of fabric, preferably of canvas, having a stuffing or filling 8, of hair, excelsior, or other material suited to the purpose, and is held combined with the bottom along the edges thereof by two strips of metal 9 and 10, through which extend rivets 11 and 12, the rivets 11 being passed only through the strips 9 and 10, thus securing them to the bottom, while the rivets 11 and 12 are passed through the strips and through the outturned edges 13 of the cushion, and thus secure the latter to the bottom. The metallic strips will generally extend from the footboard of the couch-frame to the head and may be omitted at the foot of the bottom, as the tendency for the cover to mash over at its point is but slight; but, if preferred, they may be used at the foot of the bottom if their employment will be found of advantage, and as this will be readily understood detailed illustration 80 thereof is omitted. The fabric of the cushion is continued down along the outer surface of the sides and footboard, as at 14, and is secured in position by tacks or nails 15. When the cushion has thus been secured, the mattress 16 is positioned upon the bottom and over the cushion, the mattress being of sack form and filled with any suitable stuffing 17 and is combined with the sides and footboard by tacks or nails 18. When the mattress has been assembled with the bottom and cushion in the manner described, it is then ready to receive the final external covering, which may be made of any suitable material and be tufted into lozenge or other shapes or merely be ornamented by buttons 19, which will be held in position by cords passed through the mattress and tied against the under side thereof in the usual manner.

By the employment of the marginal 100 cushion the edges of the couch-surface will be positively reinforced against any tendency to sag or mash down, and, further, the external covering will be shielded against excessive wear and strain at those points where 105 the cushion is located.

As described, the couch may be constructed without the head-section, and the crossing

spring woven-wire part and connecting strips may be used in connection with beds, chairs and sofas, and the like.

I claim—

- 5 1. A cushion-frame including a bottom, strips extending longitudinally of the bottom at each side of the frame, a marginal cushion secured to each strip, a filling interposed between the cushions, and a covering engaging the cushions.
- 10 2. A cushion-frame having a woven-wire bottom, spaced strips extending longitudinally of the woven-wire bottom at each side of the frame, a marginal cushion secured to the strips, a filling interposed between the cushions, and a covering connecting the cushions.
- 15 3. A couch-frame having a woven-wire bottom, strips secured to the woven-wire bottom, and extending longitudinal of the frame and each side thereof, a marginal cushion secured to each strip and frame respectively, a filling interposed between the cushion and a covering connecting the cushion and fastened to the frame.
- 20 4. A couch-frame having a woven-wire bottom, a longitudinal strip secured to the upper and lower surface of the woven-wire bot-

tom at each side of the frame, cushions supported by the strips, fastening devices passing through the strips and the adjacent cushions, 30 a filling interposed between said cushions and a strip of fabric extending over the filling and engaging the cushions.

5. The combination with a couch-frame provided with transverse bars, a woven-wire bottom secured to the frame, spaced longitudinal strips secured to the woven-wire bottom on each side of the frame, marginal cushions supported by the strips and secured to the latter, said cushions defining an intermediate pocket, a filling disposed within the pocket, a strip of fabric covering the pocket and extending over the marginal cushions for engagement with the cushion-frame, and springs interposed between transverse bars 45 and the woven-wire bottom.

In testimony that I claim the foregoing as my own I have hereto affixed my signature in the presence of two witnesses

MILES JOSEPH BUCKLEY.
